(57) **CLAIM**

The ornamental design for a display panel or portion thereof with a graphical user interface, as shown and described.

DESCRIPTION

FIG. 1 is a front view of a display panel or portion thereof with a graphical user interface showing a first embodiment of our design; and.

FIG. 2 is a front view of a display panel or portion thereof with a graphical user interface showing a second embodiment thereof.

The outermost broken line rectangle illustrates a display panel or portion thereof and forms no part of the claimed design. The remaining broken lines, including all text, illustrate portions of the graphical user interface or a mixed reality environment, and form no part of the claimed design.
